(57) **CLAIM**

I claim the ornamental design for a produce bin, as shown and described.

DESCRIPTION

FIG. 1 is a perspective view of a produce bin, showing my new design;

FIG. 2 is a planar top view of the produce bin;

FIG. 3 is a planar front view of the produce bin;

FIG. 4 is a planar rear view of the produce bin;

FIG. 5 is a view of one side of the produce bin;

FIG. 6 is a view of the opposite side of the produce bin; and,

FIG. 7 is a bottom view of the produce bin.

The broken lines in the drawings illustrate unclaimed environmental structure.
